No. 37,410.

Patented April 18, 1905.

UNITED STATES PATENT OFFICE.

JOHN D. O'BRYAN, OF PITTSBURG, PENNSYLVANIA.

DESIGN FOR AN ELECTRIC-LIGHT CLUSTER.

SPECIFICATION forming part of Design No. 37,410, dated April 18, 1905.

Application filed March 2, 1905. Serial No. 248,169. Term of patent 3½ years.

To all whom it may concern:

Be it known that I, JOHN D. O'BRYAN, a citizen of the United States, residing at Pittsburgh, in the county of Allegheny and State of Pennsylvania, have invented a new, original, and ornamental Design for Electric-Light Clusters, of which the following is a specification, reference being had to the accompanying drawings, forming part thereof.

Figure 1 in the drawings is a perspective

view showing my new design. Fig. 2 is another perspective view as seen from a point directly beneath the cluster.

I claim—

The ornamental design for an electric-light cluster, as shown.

JOHN D. O'BRYAN.
